SMOKER'S ARTICLE

John D. Goodell, St. Paul, Minn., assignor to Standard Packaging Corporation, a corporation of Virginia
Filed July 26, 1957, Ser. No. 674,402
3 Claims. (Cl. 131—240)

This invention relates to a novel smoker's article and more particularly to an ash tray having a cigarette holder slideably attached to a slender rod which projects upwardly from the base thereof. The cigarette holder floats freely at a fixed distance from the base of the ash tray permitting ashes from burning cigarettes and cigars to fall into the base away from the cigarette and cigars.

Permanent magnets located within the base and in the cigarette holder cause the latter to be suspended above the base of the ash tray. The repelling forces set up between the magnets in the base and in the cigarette holder provide the means of suspending the cigarette holder free of the base.

Accordingly, it is a broad object of the present invention to provide an improved smoker's article;

Another object of this invention is to provide a novel ash tray having a minimum of moving parts;

A further object of this invention is to provide an ash tray with a cigarette holder positioned above the ash receiving portion;

Another object of this invention is to provide in an ash tray having means for suspending the cigarette holder over the ash tray.

A still further object of the present invention is to provide in an ash tray means of separating cigarettes and the like from the ashes resulting therefrom;

Still another object of this invention is to provide an ash tray having magnetic means for keeping cigarettes separated from the ashes, and

A further object of the present invention is to provide in an ash tray having a cigarette holder mounted upon a center post, magnetic means for preventing the cigarette holder from gravitating or levitating from a certain position.

In the drawings:

FIGURE 1 is a top view of the invention;

FIGURE 2 is a cross-sectional view taken along line 2—2 of FIGURE 1;

FIGURE 3 is an exploded view in perspective illustrating the components of the invention; and

FIGURE 4 represents a perspective view of the invention as it appears in use.

As shown in the drawing, the preferred form of the invention utilizes a shallow base 10 for receiving ashes. Base 10 may be made of any suitable non-magnetic material such as brass, general purpose phenolic plastic, aluminum and the like. In the center of the base is a raised circular platform 11 which provides a cavity 11A (FIGURE 2) for housing various components. The base also includes a slightly sloping supporting side wall 30 and a concave inner surface 31 extending from the top of side wall 30 to the lower side of platform 11. This construction allows the base 10 to hold an ample supply of ashes and discarded cigarettes, cigars, etc. besides serving to enhance the general appearance of the entire assembly.

A cigarette holder 12 is provided which is slideably mounted upon a center post or rod 14. Rod 14 is threadedly secured to a metal insert 27 staked into the base at 17 as shown in FIGURE 3, and is made of a non-magnetic material such as brass preferably chromeplated. A plastic ball 15 is attached to rod 14 to prevent the cigarette holder 12 from becoming disengaged, as for example, when the ash tray is cleaned or when the ashes

2

are dumped out. As shown in FIGURES 2 and 3, the holder includes a main body 12A fabricated of the same material as the base, (preferably of general purpose phenolic plastic) and having horizontally disposed radially extending cigarette rests 12B located along its circumference. For the sake of appearance and for balancing purposes cigarette rests 12B are disposed at equal intervals subtending identical central angles. Although three rests 12B are illustrated in the particular embodiment under discussion it will be readily understood that any number within reason is comprehended within the purview of the invention.

Main body 12A of cigarette holder 12 has an annular recess 12C formed therein into which a washer shaped permanent magnet 24 and a spacer 25 are lodged in the manner shown in FIGURE 3. Spacer 25 may be of sponge rubber composition or any other suitable material. A hole 12D in the center of body 12A permits rod 14 to extend therethrough and a decorative panel 13 of aluminum or other suitable non-magnetic material completes the cigarette holder assembly. Lugs 13A projecting downwardly from panel 13 serve to anchor the panel into main body 12A through apertures not shown in the drawings, situated around the periphery of the main body 12A.

Base 10 is formed with an inner cavity 11A (FIGURE 2) having an annular recess similar to the annular recess 12C of cigarette holder 12. As shown in FIGURES 2 and 3 insert 27 is mounted in the central portion of the annular recess and is threaded on both ends. The upper end 27A of insert 27 is threaded to receive rod 14 while the lower end 27b is threaded to receive machine bolt 19. The base, shown assembled in FIGURE 2, has three washer shaped magnets 20, 21 and 22 of the same size and character as magnet 24 which are fitted into the annular recess or cavity 11A. Directly below magnets 20, 21 and 22 is spacer 23, similar to aforementioned spacer 25, which abuts against bottom plate 16. The entire base assembly is held together by machine bolt 19 threaded into insert 27.

In the construction shown, magnets 20, 21, 22 and 23 are of the so-called ceramic type, i.e., they are made of barium carbonate and iron oxide, obtainable in powdered form and compressed into the desired shape after which they are kiln fired and then cooled. It is important to note that the easy or preferred direction of magnetization lies along the direction of compression resulting in an effective magnetic length equivalent to the thickness of each "washer" produced. That is to say, one flat surface of each magnet is a north magnetic pole and the opposite flat surface is a south magnetic pole. The three magnets 20, 21, and 22 located in the base 10 are stacked so that the south surface of one magnet is adjacent the north surface of the next magnet thereby multiplying the total effective magnetic length by the number of magnets used, in this case three.

On the other hand magnet 24, of the same size as one of the three magnets in the base 10, is arranged so that the face thereof adjacent base 10 is of the same polarity as the top face of the uppermost magnet located in base 10. The resulting magnetic repulsion between the stack of magnets 20, 21, and 22 and magnet 24 is sufficient in strength to cause cigarette holder 12 to be freely suspended at a discrete distance from base 10, notwithstanding the influence of gravity on cigarette holder 12.

Bottom plate 16, fabricated of thin gauge steel, serves to shield the magnetic field produced by magnets 20, 21 and 22. Of interest is the fact that the cigarette holder 12 actually levitates within a roughly defined vertical zone along rod 14. That is to say, when cigarette holder 12 is in the lower regions of the aforementioned "zone," a repulsion essentially equal to the force of gravity

manifests itself. Moving cigarette holder 12 upwardly on rod 14 results in the positioning by magnetic forces of the holder at a different level above the base. This second position is thought to represent the upper extremity of the zone of magnetic influence and may be due to the convergence of magnetic lines emanating from the periphery of bottom plate 16.

It is to be understood that many other embodiments of this invention may occur to others, and therefore, the scope of invention is to be determined from the appended claims and is not to be limited by the foregoing detailed description.

I claim:

1. A cigarette ash tray comprising a molded plastic base having a concave upper ash receiving surface with a raised circular platform in the center thereof, the raised platform having an annular recess on the underside thereof, a circular shaped cigarette holder having radially extending arms for receiving cigarettes and having an annular recess therein, a first permanent magnet adapted to fit into the annular recess of said base, a second permanent magnet adapted to fit into the annular recess of said cigarette holder, said first and second magnets being substantially flat washer shaped and having their respective north and south poles disposed in such a manner that a line joining the north and south poles is perpendicular to the flat surfaces thereof, the said first magnet having a pole positioned adjacent the like pole of said second magnet thereby causing a repelling force therebetween, plate means for retaining said first magnet in said base, panel means for retaining said second magnet in said cigarette holder, and rod means for supporting said cigarette holder over said base.

2. A cigarette ash tray comprising a one piece molded base having a concave upper surface with a raised platform in the center, the raised platform being formed into an annular recess on the underside of the upper surface, a stationary first permanent magnet adapted to fit into the annular recess of said base, said first magnet having two flat surfaces with magnetic fields extending in a direction normal to the flat surfaces thereof, means for retaining said first magnet within said base, an elongated guide member releasably fastened to the raised platform of said base and extending upwardly therefrom, a cigarette holder coaxially mounted for free slideable movement along said elongated guide member, said cigarette holder having radially extending arms to hold cigarettes and having an annular recess on the underside thereof, a second permanent magnet adapted to fit into the annular recess of said cigarette holder, said second magnet having two flat surfaces with magnetic fields extending in a direction normal to the flat surfaces thereof, means for retaining said second magnet in said cigarette holder, the first and second magnets being disposed

so that their respective magnetic poles repel each other thereby causing said cigarette holder to be suspended free of said base, and means in said base for shielding said first magnet.

3. An ash tray comprising a circular base having a concaved upper ash receiving facing surface with a raised circular platform in the center thereof, said platform forming an annular recess in the downwardly facing surface of said base, a first magnetic system comprising a plurality of flat horizontally disposed circular magnets positioned in vertical symmetry within said annular recess, each magnet having a magnetic field effective in a direction normal to the flat surfaces thereof, the south pole of one magnet abutting the north pole of the adjacent magnet for reinforcing the magnetic properties of each adjacent magnet and producing the magnetic characteristics of a single magnet, an elongated rod member attached to said base and extending vertically upward therefrom, an annular cigarette holder having a centrally disposed aperture therethrough for circumventing said rod member in spaced relation from the outer surface thereof whereby said holder is free for rotatable and vertical movement along said rod member, said cigarette holder having a plurality of radially extending arcuate members for holding cigarettes, a second magnetic system comprising a flat horizontally disposed cylindrical magnet having a magnetic field effective in a direction normal to the flat surfaces thereof housed within said cigarette holder and positioned over said first magnetic system, said second magnetic system having lines of magnetic force extending downwardly therefrom of the same polarity as the lines of magnetic force extending upward from said first magnetic system for repelling the same and suspending said cigarette holder along said rod in spaced relation above said base, and a shield positioned below said first magnetic system for shielding the magnetic lines of force extending downwardly therefrom.
